UNITED STATES PATENT OFFICE

JOHN McTAMMANY, OF NEW YORK, N. Y., ASSIGNOR TO F. A. McTAMMANY,
OF NEW YORK, N. Y.

MECHANICAL MUSICAL INSTRUMENT.

No. 827,384.

Specification of Letters Patent.

Patented July 31, 1906.

Application filed February 9, 1900. Serial No. 4,594.

To all whom it may concern:

Be it known that I, JOHN McTAMMANY, of New York, in the county of New York and State of New York, have invented certain new and useful Improvements in Mechanical Musical Instruments, of which the following is a specification.

This invention has relation to mechanical musical instruments, and relates more particularly to that class of instruments in which a plurality of vibratory tongues or other sounding devices is employed in connection with mechanism for picking or sounding said tongues or sounding devices in a predetermined order or in certain relation. The said musical instruments as thus described may be divided into two subclasses—first, those in which the sounding devices are actuated by a cylinder having pins or projections to engage the teeth, and, second, those in which the sounding devices are actuated by pickers in turn receiving their power from a traveling band or belt usually called the "tune-sheet." The present invention, however, differs from the mechanisms of both of these subclasses which I have mentioned in that although a traveling tune-sheet or selector is employed it does not furnish power for actuating the pickers, the power being supplied by a means independent of said selector, and consequently said selector may be made of non-metallic material. As a result of this an elongated musical sheet may be employed, and therefore the instrument may be used for playing operas, overtures, and other classical productions, which are barred from machines employing rotary tune-sheets or pin-cylinders.

Referring to the drawings, which show one embodiment of the invention, Figure 1 represents in plan view a portion of a mechanical musical instrument with the top plate removed. Fig. 2 represents a longitudinal section through the same on the line 2 2 of Fig. 3. Fig. 3 represents one of the tilting levers in engagement with one of the toothed wheels to cause the picker to engage the tongue. Fig. 4 represents a front elevation of the same. Fig. 5 represents one of the pickers with the spring which bears against it. Figs. 6, 7, 8, and 9 represent, respectively, a spring, a picker, a toothed wheel, and a washer. Fig. 10 illustrates a portion of the perforated selector.

Referring to said drawings, *a* represents the base, from which end walls *b* and side walls *b'* rise, there being a top plate *b²*, these parts forming a box or receptacle for containing the operative mechanism. Within the box and on the base are supported standards *c c*, in which is journaled a shaft *d*, the said shaft projecting through the side wall *b'* in the present instance and being provided with a crank *d'*, by means of which it may be rotated. It will be understood that this shaft may be driven by any suitable mechanism and that I have illustrated a crank merely for the purpose of showing some device by means of which it may be rotated.

The shaft *d* is provided near its end with sprocket-wheels *d²*, of which but one is shown. In standards *e* near one end of the box is journaled a second shaft *f*, having on its ends sprocket-wheels *f'*, from which sprocket-chains *f²⁰* extend to the sprocket-wheels *d²*. Consequently by rotating the shaft *d* the shaft *f* will be rotated in the same direction at a speed governed by the relative sizes of the sprocket-wheels *d²* and *f'*. Near its ends the shaft *f* has toothed wheels *f²*, which project upward through slots in the top plate *b²* far enough for the teeth to engage apertures in the outer edges of a tune-sheet *g*, which, as indicated, is in the nature of an endless band passing around idlers *g' g'*, journaled upon suitable supports. This tune-sheet *g* passes underneath the grooved roll *h*, which is journaled upon a shaft *h'*, mounted at its ends in standards *h²*, arising from the top plate *b²*, and it is also held in engagement with the teeth of the sprocket *f²* by an idler-roll *i*, mounted in proximity to the said sprocket-wheel above the tune-sheet. There may be a single idler along each edge of the tune-sheet, or it may consist of a roll which extends entirely across it from edge to edge.

On each side of the shaft *d* there is a musical comb, said combs being placed in the same horizontal plane and being indicated at *j j*. Each of said combs is secured upon the support *j'*, in turn located upon the top of the block *j²*, as shown in Fig. 2. The plane of the tongues or sounding devices is substantially in alinement with the axis of the shaft *d*, and the ends of said tongues are equidistant from the said shaft. Placed upon the shaft is a plurality of pickers, which are normally located out of alinement with

the tongues of the comb, but which may be moved into operative position to engage the tongues and cause them to vibrate, the mechanism for moving said pickers into operative position being controlled by the perforated tune-sheet. The pickers are indicated at k k , and they consist of star-wheels or wheels having teeth or projections k' . Said wheels are formed with keys or feathers k^2 to extend into grooves or keyways m' in collars or spacers m , strung upon the shaft d . Said collars or spacers are themselves provided with keys or feathers m^2 , projecting into a groove or keyway in the shaft d . Mounted on each collar m by the side of each of the pickers k is a spur-wheel or ratchet n , which is adapted to turn loosely upon said collar. Each ratchet is provided with lateral cams n' , which, as shown, are three in number. Said cams extend normally into apertures or sockets k^3 , formed in the pickers, so that each picker and its corresponding ratchet-wheel rotate in unison. There are six apertures k^3 in each of the pickers, said apertures forming, as it were, radial spokes or ribs k^4 . If when the shaft d is rotated one of the ratchets be held stationary, the continued rotation of the corresponding picker will cause the spokes or ribs k^4 to engage the cams n' , whereby the picker will be thrust axially of the shaft away from the ratchet-wheel and into alinement with one of the tongues of each of the musical combs, and the tongues being engaged by the teeth of the picker as the shaft continues to rotate will be caused to vibrate and sound.

For the purpose of engaging the ratchets to throw the pickers automatically into alinement with their respective tongues I provide a plurality of tilting levers o , which are arranged in grooves o' in a cross-bar o^2 , attached to the top plate b^2 . Said levers are all fulcrumed upon a pin or shaft o^3 , which is passed through said bar o^2 , as shown in Figs. 3 and 4. One end of each of the levers is provided with a projection or finger o^4 , adapted to be forced up through a slot b^3 in the top plate b^2 , directly under the grooved roll h , the other end being weighted for this purpose. The last-mentioned end of the lever has a tooth or projection o^5 , which is adapted to engage one of the teeth of the ratchet n , though normally it is held out of engagement therewith by an unperforated part of the tune-sheet g . When the projection o^4 of one of the levers o registers with a perforation in the tune-sheet g , it enters the same and projects upward into one of the grooves in the roll h , and the other end is therefore dropped far enough for the projection o^5 to engage a tooth of the ratchet therebeneath and hold it against movement. The continued rotation of the shaft d , however, causes the corresponding picker to be moved axially, as previously described, whereby its

teeth will engage the corresponding tongues of the musical comb. So long as the ratchet is held against movement the tongues will be sounded by the picker.

Inasmuch as there are six teeth to each of the pickers, there are six teeth to each of the ratchet-wheels, and when the ratchet-wheel and its picker are rotating in unison the teeth thereof correspond in position with each other, the spaces k^3 in the picker being substantially equidistant between the teeth k' thereof and the cams n' being substantially intermediate or at a point midway between the teeth of the ratchet. Each picker is held against its ratchet by a circular spring p , these springs being strung upon the shaft d and lying between the collars m . Each spring is provided with three or more spring-arms p' , extending from a hub, and the ends of these resilient arms bear against a picker to hold it normally out of alinement with the tongue of the comb. The springs are splined upon the shaft, and therefore rotate, if desired, with the pickers. By reason of the construction which I have described the pickers rotate constantly during the rotation of the shaft d ; but they are moved into operative position only when the ratchets corresponding thereto are held against rotation.

I have shown two constructions of the ratchet n . In Fig. 3 the cam n' is shown as substantially midway between the teeth of the ratchet, whereas in Fig. 8 the cams are located in the radial lines of said teeth. In either event, however, the operation will be substantially the same.

The tune-sheet g is provided in its edge with a row of equally-spaced apertures to receive the teeth of the driving-sprocket f^2 , so that the speed of the sheet is controlled directly by the sprockets instead of by the winding-roll. In this connection it may be stated that it has been customary to move the elongated selector by a winding-roll. This is objectionable in that the accumulation of the coils of the selector upon the winding-roll constantly accelerates the speed of the selector and destroys the tempo or movement of the musical composition. In the herein-described instrument, however, the selector is fed by the sprockets at an unvarying rate of speed.

In addition to preventing a change in the tempo or movement of the composition I achieve another object in the operation of the instrument. The cams on the ratchet-wheels are so formed as to practically preclude the likelihood of their indefinitely riding upon the spokes k^4 of the pickers, thereby prolonging a tone indefinitely; but as a further precaution against such a contingency the note-holes in the selector are in such relation to the sprocket-holes that the engagement of the cams n' with the spokes k^4 is properly timed.

The operation of the instrument is as follows: The shaft d is rotated, thereby causing the feeding of the tune-sheet through a sprocket-chain f^o , the sprocket-wheels d^o and f' , and the spur-wheel f^2 . When the perforation registers with the projection o^4 on one of the tilting levers, the latter passes up through the sheet into the groove h^2 , causing the opposite end of the lever to descend and engage a tooth of the ratchet-wheel. The latter is immediately stopped from turning, and its corresponding picker is moved longitudinally of the shaft to cause its teeth to engage the combs and sound the same. When the solid portion of the tune-sheet impinges against the end o^4 of the tilting lever, it is returned to its normal position and releases the ratchet, which turns on its axis until its cams enter the apertures in the pickers, this being effected by the flat spring which bears thereagainst and causes the ribs or spokes to ride down the inclined sides of the cams n' . The flat springs not only act as washers to separate the collars m , but with the ratchet-wheels form raceways for the reception of the laterally-movable pickers.

I have referred to the devices which act upon the combs as "pickers" and "ratchets;" but I may also term them both "star-wheels," in which case the wheels which are engaged by the tilting levers are termed "primary" star-wheels and those which engage the tongues of the combs are termed the "secondary" star-wheels. Viewed in this light, it may be stated that between the tune-sheet and the combs there is mechanism including a secondary star-wheel to engage the comb and a primary star-wheel to cause the latter to pick the teeth of the comb. This is true even though the power for moving the secondary star-wheel is derived from the rotating shaft.

Having thus explained the nature of the invention, it is declared that what I claim, and desire to secure by Letters Patent, is—

1. In a mechanical musical instrument, the combination with a tune-sheet, of a plurality of sounding devices, a series of primary and secondary star-wheels having coacting cams and intervening mechanism between the sheet and the primary star-wheels whereby said primary star-wheels act upon the secondary star-wheels to cause the latter to actuate the sounding devices.

2. In a mechanical musical instrument, the combination with a tune-sheet, of a series of independently-acting rotary pickers, each laterally movable independently of the others.

3. In a mechanical musical instrument, the combination with a series of sounding devices, of a series of independent star-wheels or pickers, said wheels being rotatable and being axially movable independently of each other.

4. In a mechanical musical instrument, the

combination with a plurality of sounding devices, of a plurality of pickers normally out of alignment with the sounding devices, and mechanism by means of which said pickers are caused to engage the said teeth. 70

5. In a mechanical musical instrument, the combination with a series of sounding devices, of a plurality of pickers normally out of alignment with the sounding devices, means for actuating said pickers, and means for selecting predetermined pickers and moving them into alignment with the sounding devices. 75

6. In a mechanical musical instrument, the combination with a series of sounding devices, of a plurality of independent continuously-actuated pickers, normally inoperative with respect to the sounding devices, and means for selecting said pickers in predetermined order and causing them to engage their respective sounding devices. 80

7. In a mechanical musical instrument, the combination with a series of sounding devices, of a plurality of rotary pickers normally inoperative with respect to the sounding devices, means for continuously rotating said pickers, a perforated tune-sheet or selector, and means controllable by the perforations in said tune-sheet for selecting in predetermined order the pickers which are to be rotated to engage said sounding devices. 85

8. In a mechanical musical instrument, the combination with a plurality of sounding devices, of a plurality of rotary pickers movable in the direction of their axes of rotation, means for continuously rotating said pickers, and a selector independent of said means and having perforations for causing the pickers when rotated and selected to engage the sounding devices in predetermined order. 90

9. In a mechanical musical instrument, the combination with a series of sounding devices, of a plurality of pickers, means for actuating said pickers simultaneously, a tune-sheet, and mechanism intervening between said tune-sheet and said pickers for selecting certain of said pickers to engage their respective sounding devices. 105

10. In a mechanical musical instrument, the combination with a series of sounding devices, of a plurality of pickers, means for actuating said pickers in unison, and cam devices for each picker for causing it to engage a sounding device. 115

11. In a mechanical musical instrument, the combination with a comb, of a plurality of pickers for engaging the teeth of the comb, said pickers being normally in inoperative position with respect to said teeth, a selector, mechanism intervening between the selector and the cam devices to select them in predetermined order, and a plurality of cam devices for moving said pickers laterally into operative position with respect to the comb-teeth. 125

12. In a mechanical musical instrument, 130

- the combination with a series of sounding devices, of a rotary shaft, means for rotating said shaft, a plurality of pickers mounted on said shaft to continuously rotate therewith, 5 means for holding said pickers in inoperative position with relation to the sounding devices, and selecting mechanism for moving said pickers into operative position to engage said sounding devices.
- 10 13. In a mechanical musical instrument, the combination with a series of sounding devices, of a rotary shaft, means for rotating said shaft, a plurality of star-wheels on said shaft to pick the sounding devices, a tune- 15 sheet, and intervening mechanism between the star-wheels and the tune-sheet whereby said star-wheels are selected in predetermined order to engage the sounding devices.
14. In a mechanical musical instrument, 20 the combination with a series of sounding devices, of a plurality of star-wheels for engaging the sounding devices, cam devices for engaging each star-wheel and means controlled by a tune-sheet for causing said cam devices 25 to effect the picking of a sounding device by its respective star-wheel.
15. In a mechanical musical instrument, the combination with a series of sounding devices, of a rotary shaft, a plurality of star- 30 wheels on said shaft and out of alinement with the sounding devices, a ratchet for each star-wheel, said ratchets having cam devices to act on said star-wheels to move them into alinement with the sounding devices, and 35 normally rotating with said star-wheels and mechanism adapted to be controlled by a tune-sheet for engaging the ratchet-wheels in predetermined order and hold them against rotation.
- 40 16. In a mechanical musical instrument, the combination with a series of sounding devices, a plurality of primary and secondary star-wheels, a shaft on which said star-wheels are all mounted, means for engaging and 45 stopping the rotation of the primary star-wheels, and cam devices carried by the said primary star-wheels for causing the secondary star-wheels to engage the sounding devices.
- 50 17. In a mechanical musical instrument, the combination with a series of sounding devices, and means for feeding a tune-sheet, of a series of independent pickers controlled by said tune-sheet for picking the sounding devices, said pickers having continuous rotary 55 and independent lateral movements.
18. In a mechanical musical instrument, 60 the combination with means for feeding a perforated tune-sheet, and a series of sounding devices, of a plurality of fingers controlled by the perforations in the tune-sheet, a series of star-wheels acted on by said fingers, and secondary star-wheels acted on by the first-mentioned star-wheels for engaging the 65 sounding devices.
19. In a mechanical musical instrument, the combination of a series of sounding devices, and a plurality of star-wheels independently movable laterally to engage the sounding devices. 70
20. In a mechanical musical instrument, the combination with a series of sounding devices, of a series of tilting levers and a plurality of continuously-rotating star-wheels caused by said tilting levers to engage the 75 teeth of the comb.
21. In a mechanical musical instrument, the combination with a series of sounding devices, of a plurality of secondary star-wheels for engaging the sounding devices, a similar 80 number of tilting levers adapted to be controlled by a tune-sheet, and a similar number of primary star-wheels controlled by the tilting levers for causing the secondary star-wheels to engage and sound the sounding de- 85 vices.
22. In a mechanical instrument, the combination with musical combs arranged opposite each other, of a shaft intermediate of said combs, a plurality of pickers on said shaft, 90 and lying normally out of alinement with the teeth of said combs, and mechanism for moving said pickers axially of said shaft to engage the corresponding teeth on both combs simultaneously. 95
23. In a mechanical musical instrument, the combination with a sounding device, of a rotary shaft, two star-wheels mounted on said shaft, provisions whereby one star-wheel controls the action of the other, a tilting lever for engaging the first-mentioned star-wheel, and a selector for governing the action of the tilting lever. 100
24. In a mechanical musical instrument, adapted to be operated by a perforated sheet, 105 the combination of a sound-producing device, a continuously-rotating star-wheel adapted to actuate the same but normally in inoperative relation thereto, and a star-wheel intervening between the music-sheet and said first-mentioned star-wheel, and having provisions for moving said first-mentioned star-wheel to operative position. 110
25. In an automatic musical instrument adapted to be operated by a perforated sheet, 111 the combination of a series of sounding devices, two star-wheels for each sounding device, and a series of tilting levers intervening between the star-wheels and the perforated sheet. 112
26. In a mechanical musical instrument, the combination of a shaft, a series of collars mounted on said shaft to turn therewith, said collars having a series of grooves extending axially of the shaft, a series of star-wheels 113 having projections fitted in said grooves, another series of star-wheels rotatable on said collars, and a series of spring-washers holding the second-mentioned star-wheels against the first-mentioned star-wheels. 114

27. In a mechanical musical instrument, the combination with a sounding device, of a rotary shaft, a series of spring-washers, pickers on said shaft alternating with said spring-

5 washers, and means for imparting an axial movement to said pickers independently of each other against the sides of the spring-washers.

28. In a mechanical musical instrument, the combination with a toothed comb, of a plurality of spring-tensioned pickers normally out of alinement with the teeth of said comb, and selecting mechanism for moving said pickers against the pressure of their 15 springs into alinement with the teeth of the comb.

29. In a mechanical musical instrument, the combination with a toothed comb, of a rotary shaft, a plurality of collars keyed on 20 said shaft, a picker keyed on each collar but movable axially thereon, said pickers being normally out of alinement with the teeth of the comb, a ratchet mounted loosely on each collar, said ratchets having cam devices fitting 25 in apertures or sockets in the pickers, and selecting mechanism for engaging and temporarily holding said ratchets against rotation for the purpose described.

30. In a mechanical musical instrument, the combination with wheels for engaging 30 and feeding a tune-sheet, and a toothed comb, of a continuously-rotating shaft, a plurality of pickers mounted on said shaft to rotate synchronously therewith, power-transmitting 35 devices between said shaft and the said wheels, and provisions controlled by said tune-sheet for causing said pickers to engage the teeth of said comb.

31. In a mechanical musical instrument, the combination of a sounding device, a rotary picker normally in inoperative relation 40 to said device, means for continuously rotating said picker, a tune-sheet having perforations, means for moving said picker into operative relation to said device, and means 45 controlled by said perforations for causing said picker to operate said device when moved into operative relation thereto.

32. A mechanical musical instrument comprising a plurality of sounding devices, a perforated selector, a plurality of rotary pickers movable in the direction of their axes of rotation adapted to be selected in any predetermined order by the perforations in the selector, and means independent of the selector for continuously rotating said pickers whereby as they are selected by said selector, they pick the sounding devices.

33. A mechanical musical instrument, comprising a plurality of sounding devices, a plurality of rotary pickers movable in the direction of their axes, a selector having perfora-

tions governing the order in which said pickers operate said sounding devices, and means independent of said selector for continuously 65 actuating said pickers.

34. A mechanical musical instrument comprising a sounding device, a multiple-pointed rotary picker movable in the direction of its axis of rotation and normally inoperative 70 with respect to said sounding device, a selector having perforations which govern the action of the picker, and means independent of said selector for continuously actuating said picker. 75

35. A mechanical musical instrument comprising a sounding device, a multiple-pointed picker, a selector having perforations governing the engagement of the points of said picker with said sounding device, and means 80 independent of the selector for continuously rotating said picker to bring its points successively into engagement with said sounding device when said picker is selected by said selector, said picker being movable in the direction of its axis of rotation. 85

36. A mechanical musical instrument, comprising musical combs arranged opposite to each other, a selector or tune-sheet, a plurality of pickers, and mechanism independent of 90 said tune-sheet or selector and including a driving-shaft intermediate of said combs for actuating the pickers to cause them to pick the teeth of the combs, the pickers being on said shaft. 95

37. A mechanical musical instrument comprising a plurality of sounding devices, a shaft, a pair of toothed wheels on said shaft for each sounding device, and a selector for governing the action of said wheels. 100

38. A mechanical musical instrument comprising a continuously-rotating shaft, a plurality of sounding devices, a plurality of toothed wheels on said shaft for each sounding device, and a selector governing the action 105 of said wheels.

39. A mechanical musical instrument, comprising a sounding device, a rotary picker for engaging and releasing said sounding device, said picker being movable in the direction of 110 its axis of rotation and normally inoperative with respect to said sounding device, a selector having perforations which control the axial movement of said picker into engagement with the sounding device, and means 115 independent of the selector for continuously and positively actuating said picker.

In testimony whereof I have affixed my signature in presence of two witnesses.

JOHN McTAMMANY.
